UNITED STATES PATENT OFFICE.

WILLIAM F. REACH, OF CHICOOPEE, MASSACHUSETTS, ASSIGNOR TO A. G. SPALDING & BROS., OF NEW YORK, N. Y., A CORPORATION OF NEW JERSEY.

PRESS FOR TENNIS RACKETS AND THE LIKE.

Application filed December 24, 1923. Serial No. 682,387.

To all whom it may concern:

Be it known that I, WILLIAM F. REACH, a citizen of the United States, residing at Chicopee, in the State of Massachusetts, have invented

5 certain new and useful Improvements in Presses for Tennis Rackets and the like, of which the following is a specification, reference being had to the accompanying drawing, forming a part hereof.

10 This invention relates to a tennis racket press and more particularly to improvements therein which will render the press highly efficient in use and simple in construction.

15 The invention has for an object the provision of a tennis racket press which will be of such construction that the racket may be readily placed therein or removed as desired by simply releasing one corner of the

20 press thereby making it unnecessary to open the entire press or disconnect the opposite frames thereof. It has heretofore been proposed to permit the release of one corner of the press by pivoting the usual bolt at that

25 corner in one of the clamping frames and forming the co-operating frame with a slot into which the bolt may be swung to engage that frame by means of the winged nut threaded on the bolt.

30 The present invention is considerably simplified over previous means for releasing one corner of the press since there is no pivoted joint to complicate the manufacture of the frame and no slot extends into the side of the cooperating frame for an appreciable distance to weaken that member.

According to the present invention one of the clamping frames is provided with an aperture at one corner thereof of a diameter sufficient to permit the passage of the shank of the bolt but insufficient to permit the passage of the head thereof, while the co-operating frame is provided with an aperture in register with the first mentioned aperture which is of a diameter sufficient to permit the passage of the head of the bolt, means being provided on the co-operating clamping frame to engage the head of the bolt and prevent its withdrawal through the aperture of larger diameter. Such means may conveniently take the form of a slide having one end bifurcated to engage the shank of the bolt beneath its head.

35 A preferred embodiment of the invention will now be described more fully with refer-

ence to the accompanying drawings in which:

Figure 1 is a perspective view of the improved form of press.

Figure 2 is a detail sectional view taken 60 on the plane indicated by the line 2—2 in Figure 1 looking in the direction of the arrows, and showing the relation of parts in operative position.

Figure 3 is a similar sectional view but 65 showing the bolt in its retracted position to permit the withdrawal or insertion of a tennis racket.

Referring more in detail to the drawings in which similar reference characters designate corresponding parts throughout the several views 4 and 5 indicate the frames of the press which are of rectangular form and similarly constructed of wood, as disclosed, or from any other suitable or preferred material. The frames are preferably formed of side members some of which are provided at their ends with mortises 6, while other frame members are formed with tenons 7 fitting in the mortises 6. The frame members are all 80 rounded at their ends to present rounded corners 8 for the frames. At the corners, the frames are connected in parallel relationship by bolts 9 passing through registering apertures in the two frames and bearing on the outer side of one frame by means of the head 10 and on the opposite side of the other frame by means of the winged nuts 11 or the like. Expansion springs 12 are positioned upon three of the bolts 9 to press 90 outwardly upon the frames 4 and 5 and resiliently retain them in spaced relation. At the remaining corner of the frames 4 and 5, they are provided with connecting means which can be readily disassociated to facilitate the withdrawal or insertion of a tennis racket. To this end one of the frames, say 4, is formed with an aperture 13 of a diameter sufficient to receive the shank of the bolt but insufficient to permit the passage of the head 10 therethrough. The other frame, say 5, is provided with an aperture 14 in register with 13 but of a diameter insufficient to permit the passage of the head 10 therethrough.

100 In order to retain the bolt in the position indicated in Figure 2, means are carried with frame 5 to engage the bolt and prevent the passage of the head 10 through the aperture 14. This means may conveniently take the form of a bifurcated mem- 105
110

ber 15 held in sliding relationship with the outer surface of frame 5 by means of a bracket 16 secured in any convenient manner as by screws 17 to the frame 5. The 5 end of the slide 15 is conveniently up-turned as at 18 to facilitate the retention of the slide by the bracket while at the bifurcated end 19, the shoulders 20 form convenient stops for the same purpose. In order to permit the bolts 9 to be rigidly held in the frame member 5, a portion of the shank adjacent the head 10 may, if desired, be formed with a rectangular cross section as indicated at 21 in Figures 2 and 3. This construction 10 is particularly advantageous since by making the inner sides of the bifurcated end 20 of the slide 15 substantially parallel, such bifurcated end when engaging the shank portion 21 prevents the rotation of the bolt 15 when the winged nut 11 is turned. It will be obvious that means other than the slide 15 might be provided to engage the shank of the bolt. For instance, hook-shaped member 25 might be substituted for the slide and when pivoted to the frame 5 could be swung in a plane parallel to the frame into engaging position beneath the head 10.

It is believed that the complete construction and operation of the press will now be 30 apparent from the foregoing description taken in connection with the accompanying drawings. The operation may be briefly set forth as follows: When it is desired to place a tennis racket within the press or to 35 remove the tennis racket, the winged nuts 11 are rotated to permit the separation of the frames 4 and 5 under influence of the springs 12. The bolt 9 at the corner provided with the aperture 14 of increased diameter should then be released by movement of the slide 15 and the bolt withdrawn to the position indicated in Figure 3 to provide a clearance for the passage of the racket. After the racket has been placed 40 within the press or removed, the head 10 of bolt 9 may be passed through aperture 14 to the position indicated in Figure 2 and slide 15 moved to engage the head of the bolt. To draw the frames 4 and 5 together 45 into clamping relationship with the racket, it is then only necessary to take up on the bolts at all four corners by means of the winged nuts 11. It is therefore evident that any corner or side of the frames 4 and 5 50 may be tightened or tensioned upon the racket or other member within the press, independent of the remaining corners or sides of the frame. Furthermore, it is evident that the racket may be readily inserted, adjusted in or removed from the press without 55 the necessity of disconnecting completely the frames 4 and 5. It is also evident that the use of the press need not be limited to tennis rackets.

60 65 While the preferred embodiment of the

invention has been disclosed, it is to be understood that changes may be resorted to in the bolt and engaging means without departing from the spirit of the invention and no limitation is intended other than as indicated in the appended claims.

What I claim is:

1. In a press, co-operating frames, means to connect said frames, one of said frames being formed with an aperture, a bolt passing through said aperture and having a head of greater diameter than the diameter of the aperture, said co-operating frame being formed with an aperture in register with said first mentioned aperture and of a diameter sufficient to permit the passage of the head of the bolt and means carried with said second mentioned frame to engage the bolt. 75

2. In a press, two co-operating clamping frames, means to connect said frames, one of said frames being formed with an aperture, a bolt passing through said aperture and having a head of a diameter greater than the diameter of said aperture, a co-operating frame formed with an aperture in register with said first mentioned aperture and of a diameter sufficient to permit the passage of the head of the bolt, and a slide carried with said last mentioned frame and formed with a bifurcated end to engage the bolt. 85

3. In a press, co-operating frames, means to connect said frames, one of said frames being formed with an aperture, a bolt passing through said aperture and having a head of greater diameter than the diameter of the aperture, a co-operating frame formed with an aperture in register with the first mentioned aperture and of a diameter sufficient to permit the passage of the head of the bolt, a member carried with said last mentioned clamping member and formed with a slot of a diameter sufficient to permit the passage of the shank of the bolt but of less diameter than the head of the bolt. 100

4. In a press, co-operating frames, one of said frames being formed with an aperture, a bolt passing through the aperture and formed with a head of greater diameter than the diameter of the aperture, and a shank portion of rectangular cross section adjacent said head, a co-operating frame formed with an aperture in register with said first mentioned aperture and of a diameter sufficient to permit the passage of the head of the bolt, a slide formed with a bifurcated end having parallel sides to engage the rectangular portion of the shank of the bolt, and means to retain the slide in sliding relationship with said frame member. 105 110 115 120 125

This specification signed this 20th day of December A. D. 1923.

WILLIAM F. REACH.
